United States Patent Office.

IMPROVED SHEEP-SHED.

J. KNUPP AND H. S. ELLIOTT, OF NEW PROSPECT, OHIO.

Letters Patent No. 60,015, dated November 27, 1866.

SPECIFICATION.

TO ALL WHOM IT MAY CONCERN:

Be it known that we, KNUPP & ELLIOTT, of New Prospect, in the county of Wayne, and State of Ohio, have invented certain new and useful improvements in the mode of constructing Sheep-Sheds; and we do hereby declare that the following is a full and complete description thereof, reference being had to the accompanying drawings, making part of this specification, in which—

Figure 1 is a perspective view of the shed.

Figure 2 is a longitudinal section of the same.

Figure 3 is a transverse section.

Like letters of reference refer to like parts in the different views.

This barn consists of a light wooden frame-work, as shown in fig. 2, and may be enclosed and shingled in the ordinary manner; it is also constructed in four sections, A B, fig. 1, and C D, fig. 2. By this it will be seen that it is divided longitudinally and transversely into four equal divisions, and are temporally locked together by the ties E, figs. 1 and 2, and which may be unlocked and taken apart for purposes hereafter shown. Each of these sections is mounted upon runners F, figs. 1 and 2, to which reference will hereafter be made. G, fig. 1, are side doors through which the sheep enter the shed; H a door through which access is had to the stalls or pens for the purpose of feeding, &c. The internal arrangement of the shed is as follows: Through the entire length of the building is a passage way, J, fig. 3, which is closed by the door, H, above referred to; on each side of this passage is the sheep room, K, which may be divided into stalls or pens if so desired; a is a feeding trough, running the length of the building, one on each side of the passage, and it is so arranged that one-half of the width of the trough is in the sheep room, and the other half in the passage. L, fig. 2, are drop doors, and are so hinged by the hook and eye, c, to the girt M, as to allow of their being raised in the passage way only; the purpose of these doors is to keep the sheep from getting through into the passage. N is a rail, and is so hinged to the girt, M, as to permit of its being turned upward; to this rail are attached the doors by the hook and links, d.

Having thus described the construction and internal arrangement of the building, we will now describe the management of the same, which is as follows:

The sheep are allowed to enter the shed by the doors, G, referred to, one being at each end of the side division; if grain is to be fed to the flock, it is placed in the trough from the passage, thus avoiding the necessity of going among them for that purpose, and thereby avoiding the danger of spilling the grain, by the crowding of the sheep to the trough, or the trouble of turning them out of the shed in order to feed them. It will be seen by this that the flock can be fed in rainy or stormy weather without exposing them to the severity of the storm. The doors L, being attached to the rail M, in the manner as above described, they can thereby be all raised up at the same time, and more or less as circumstances may require. Hay is fed to the flock by throwing it along the passage close to the trough, the doors being raised so that the sheep can reach through to it. Thus it is at all times kept clean and protected from the storms.

When it is desired to move this shed from one place to another, the several sections are detached, and each being placed upon runners as above stated, it can be drawn to any place desired, and again locked in the manner as above described. Or should it be so desired, each section may be used separately, or two sections together, as may best suit the wants and convenience of the sheep-master.

What we claim as our invention, and desire to secure by Letters Patent, is—

The construction and arrangement of a shed B, in combination with the trough d, doors L, rail N, and runners F, for the purpose and in the manner as set forth.

JACOB KNUPP,
HENRY S. ELLIOTT.
